UNITED STATES PATENT OFFICE.

JOSEPH B. CURRAN, JR., OF NEW YORK, N. Y.

DESIGN FOR AN EMBLEM, BROOCH, BUTTON, FOB, OR SIMILAR ARTICLE.

56,655.

Specification for Design. Patented Nov. 23, 1920.

Application filed July 29, 1920. Serial No. 399,907. Term of patent 3½ years.

To all whom it may concern:

Be it known that I, JOSEPH B. CURRAN, Jr., a citizen of the United States, and a resident of the city of New York, borough of the Bronx, in the county of Bronx and State of New York, United States of America, have invented a new, original, and ornamental Design for an Emblem, Brooch, Button, Fob, or Similar Article.

Reference is to be had to the accompanying drawing, in which—

The figure is a face view of an emblem, brooch, button, fob, or similar article showing my new design.

I claim:

The ornamental design for an emblem, brooch, button, fob, or similar article, as shown.

JOSEPH B. CURRAN, JR.
